INTERNAL-COMBUSTION ENGINE OPERATING ON THE TWO-STROKE CYCLE

Application filed January 29, 1929, Serial No. 335,920, and in Switzerland February 10, 1928.

This invention relates to internal combustion engines operating on the two-stroke cycle of the kind in which a scavenging charge is admitted and exhaust gases escape 5 respectively through ports situated in the cylinder wall.

In known engines of this type either the scavenging charge is admitted always in the same direction and the exhaust gases are 10 discharged through an exhaust port situated on the same or the opposite side of the cylinder to the scavenging ports, or the scavenging charge is directed, during the initial part of the scavenging period, towards the centre of 15 the cylinder owing to the shape or construction of the port or ports and subsequently towards the end of the scavenging period, is deflected more along the cylinder wall. In the first of the above prior arrangements not 20 only are rotating cores of exhaust gases apt to be formed in the centre portion of the cylinder but further the corners of the cylinder are not efficiently scavenged, while in the second prior arrangement the contents of 25 the cylinder are so swept through by the scavenging charge that the desired purity of charge is not attained even with considerable consumption of scavenging air.

According to the present invention the air 30 inlet ports are subdivided and the charge entering therethrough is caused during the initial part of the scavenging period to flow along the cylinder wall towards the cylinder head and subsequently is gradually deflected 35 obliquely towards the cylinder axis so as to expel the exhaust gases through one or more exhaust ports disposed opposite to the scavenging port.

The means employed to effect the desired 40 change in direction of the scavenging charge may vary. Thus the flow through the subdivision or subdivisions of the air inlet ports which are uncovered by the piston during the initial part of the scavenging period may 45 be caused to take place in a different direction from that through the subdivision or subdivisions uncovered during the later part of the scavenging period. Alternatively, the desired change in direction of flow of the 50 scavenging charge may be effected by a sec-

ondary scavenging charge admitted into the cylinder so as to strike the main scavenging charge and deflect it in the desired manner, the manner in which the main and secondary scavenging charges are admitted being such 55 that the effect of the secondary scavenging charge on the direction of flow of the main scavenging charge varies throughout the scavenging period so as to produce the desired variation in the direction of flow of the main scavenging charge. In such an arrangement the rate of flow of the secondary scavenging charge at its admission into the cylinder is conveniently greater than that of the main scavenging charge. 60

In any case the upper edge of the main scavenging port or ports preferably lies above the upper edge of the secondary scavenging and exhaust ports so as to avoid undue throttling of the charge entering the cylinder during the later part of the scavenging period. 65

Further where a secondary scavenging charge is employed, this is conveniently admitted in such a manner as to prevent as far as possible a premature escape of the scavenging charge from the engine cylinder through the exhaust port or ports. 70

The invention may be carried into practice in various ways but various constructions according to this invention are illustrated diagrammatically by way of example in the accompanying drawings, in which— 75

Figure 1 shows diagrammatically the manner in which scavenging air flows into the cylinder in known prior arrangements, 80

Figure 2 shows diagrammatically the manner in which scavenging is effected according to the present invention, 85

Figures 3 and 4 show one construction in which scavenging is effected in the manner 90 according to the present invention,

Figure 5 shows one alternative construction according to this invention, and

Figures 6, 7 and 8 show another alternative construction according to this invention. 95

In the previously known arrangement as illustrated in Figure 1 in which the scavenging air was admitted into the cylinder 7 through non-subdivided scavenging ports 6, and the flow of the scavenging air took place during 100

the scavenging period successively in the directions indicated by the arrows 5, 4, 3, 2, 1, in Figure 2, this air impinged first against the opposite cylinder wall and was deflected thereby upwards whereby rotating cores of burnt gases as indicated at *a* and *b* in Figure 1 were apt to be formed in the cylinder and to effect adversely the combustion on the next power stroke.

10 In an engine according to the present invention, however, flow through the main scavenging port 6 takes place successively in the directions indicated by the arrows 1, 2, 3, 4, 5 in Figure 2. That is to say, during 15 the initial scavenging period, say when the crank is in position 1 indicated in Figure 2, the scavenging air flows in the direction indicated by the arrow 1 and as the crank advances successively through the positions 2, 20 3, 4 and 5 so the direction of flow of the scavenging air is also deflected so as to follow successively the direction of the arrows 2, 3, 4 and 5. Thus the exhaust gases are expelled 25 through the exhaust port 8 under the action of the scavenging air current as it swings downwards.

In Figure 2 the scavenging port 6 is not shown as subdivided as it would be in practice since the purpose of this figure is merely 30 to indicate diagrammatically the manner in which scavenging is effected according to this invention.

The change in direction of flow of the main 35 scavenging air current during the scavenging period may be effected in various ways. For example, as shown in Figures 3 and 4, the partitions subdividing the scavenging port 6 may be in the form of movable guide 40 vanes 11 pivoted about horizontal axes 9 and adapted to be rocked during the scavenging period by a control rod 10 pivoted thereto. Figure 3 indicates the condition during the initial part of the scavenging period in which the scavenging air current is directed along the cylinder wall towards the cylinder head in the direction indicated by the arrow 1. As the scavenging period progresses so the guide vanes 11 are rocked by the rod 10 so that during the later part 45 of a scavenging period as the piston 12 moves upward as indicated in Figure 4, the scavenging air current is deflected towards the centre of the cylinder in the direction of the arrow 5.

50 In order to avoid undue throttling of the scavenging air towards the end of the scavenging period, the subdivided scavenging ports 6 conveniently extend upwards above the level of the upper edge of the exhaust ports 8 as shown.

In the alternative arrangement indicated 55 in Figure 5, the change of direction of flow of the main scavenging air current is effected by means of a secondary or auxiliary scavenging air current admitted through a

port 14 from the side of the cylinder adjacent to the exhaust port 8. In this arrangement the main scavenging ports 6 are arranged as before opposite to the exhaust port 8 and are subdivided by means of fixed guide vanes 13, the secondary scavenging air ports 14 lying beneath the exhaust ports 8.

Thus when after equalization of pressure has taken place following the uncovering of the exhaust ports 8, the main scavenging charge enters through the main scavenging ports 6, for instance in the direction of the arrow 15, this main scavenging charge will be deflected along the adjacent cylinder wall by the secondary scavenging air current entering in the direction of the arrow 16 so that there will be produced a scavenging air current due to the two currents in the direction of the arrow 17. Owing to the increase in the cross-sectional area of the secondary scavenging ports 14 due to the downward movement of the piston 12, the effect of the secondary scavenging air current on the direction of flow of the main scavenging air current will be reduced as the piston descends and the main scavenging air current will become deflected as the scavenging period progresses as indicated by the arrow 18 towards the centre of the cylinder in the manner according to this invention.

A still further arrangement for carrying out the present invention is shown in Figures 6, 7 and 8. This arrangement is somewhat similar to that shown in Figure 5 except that the upper and lower divisions 20, 21 of the main scavenging port communicate with separate chambers having a valve 22 dividing them.

Figure 6 shows the condition during the initial part of a scavenging period during which after equalization of pressure has taken place the main scavenging air will flow through the lower scavenging ports 21, which may be shaped so as to direct the air more towards the cylinder head, and will be deflected at first along the cylinder wall by the secondary scavenging air current entering at higher speed through the ports 14 so that there will take place during the initial part of the scavenging period scavenging of the outer parts of the cylinder. The air entering through the upper main scavenging ports 20 will not, at this stage, have any considerable effect on the direction of flow of the scavenging current, since the rate of flow through the ports 20 is reduced owing to the air flowing to this port having to open and pass through the valve 22.

As the scavenging period progresses the secondary scavenging ports 14 will be opened further and the rate of flow of air therethrough will decrease so that the action of the secondary scavenging air current on the main scavenging air current will be reduced and the main scavenging air current will thus

enter the cylinder obliquely as shown in Figure 7. Towards the end of the scavenging period the direction of flow of the main scavenging air current will be substantially that of the flow through the upper ports 20 as indicated in Figure 8, since at this stage air can flow with undiminished velocity through these ports, the valve 22 being now open. Thus during the later portions of the scavenging period, the main scavenging air current is directed towards the centre of the cylinder to expel any traces of waste gases which may still remain.

With either of the arrangements illustrated in Figure 5 or in Figures 6, 7 and 8, a further improvement as regards the consumption of scavenging air may be obtained by admitting the secondary scavenging air current into the cylinder in such a manner as to avoid as far as possible a premature escape of air from the engine cylinder into the exhaust.

In order to show more clearly the manner in which the direction of flow of the main scavenging air current varies according to this invention, the subdivided main air scavenging port as well as the exhaust ports are indicated in the drawings merely diagrammatically. In practice it is advisable to arrange the air inlet ports 20 and 21 on one side of the cylinder and the exhaust ports 8 on the opposite side of the cylinder, and to arrange the secondary scavenging air ports 14 beneath the latter so as to extend throughout their length considered circumferentially of the cylinder. Further, if desired, the secondary scavenging air ports may be constructed so that the air current is admitted into the cylinder in a direction approximately at right angles to the axis of the piston instead of inclined thereto as shown.

Again, the exhaust port may be controlled by separate valves instead of by the piston while the desired effect may be obtained in other ways than by admitting the scavenging air in different directions through the various subdivisions of the main scavenging port, by employing secondary scavenging currents or by providing movable guide vanes in the main scavenging ports without departing from this invention.

I claim:

1. In a two-stroke internal combustion engine, a cylinder having a set of principal, sub-divided, scavenging ports on one side of the cylinder, and a set of secondary scavenging ports arranged on the opposite side thereof, the relation between the arrangement of said ports being such that a stream of air introduced through said principal ports during the scavenging period will be deflected by an impinging stream of air introduced through said secondary ports and directed first axially of the cylinder and subsequently

at a gradually increasing angle to the cylinder axis.

2. Apparatus according to claim 1, further characterized by a set of exhaust ports said ports being located on the opposite side of the cylinder from the principal sub-divided scavenging ports, said exhaust ports being arranged above said secondary scavenging ports.

3. Apparatus according to claim 1, including means for closing the principal sub-divided scavenging ports later than the other in order to avoid throttling.

4. A method of scavenging the cylinder of a two-stroke internal combustion engine, comprising applying a principal scavenging force in a certain direction within the cylinder, and applying against this force a secondary force, said secondary force being directed against said principal force in such a direction as to deflect the resultant first towards the end of the cylinder and thereafter obliquely towards the cylinder axis.

5. A method of scavenging the cylinder of a two-stroke internal combustion engine, comprising applying a principal scavenging force in a certain direction within the cylinder, and applying against this force a secondary force in a direction substantially at right angles thereto.

6. A method according to claim 4, further characterized by the fact that the secondary force is applied with an initial value greater than that of the principal force.

7. A method according to claim 4, in which the secondary force is so combined with the other force in the cylinder as to prevent premature exhaust from the cylinder.

In testimony whereof I have affixed my signature.

PETER FOTH.
